UNITED STATES PATENT OFFICE.

AUGUSTUS MAY, OF NEW ORLEANS, LOUISIANA.

FOLDING GARMENT-RACK.

No. 927,369.

Specification of Letters Patent.

Patented July 6, 1909.

Application filed February 19, 1909. Serial No. 478,843.

To all whom it may concern:

Be it known that I, AUGUSTUS MAY, a citizen of the United States, residing at New Orleans, in the parish of Orleans and State of Louisiana, have invented new and useful Improvements in Folding Garment-Racks, of which the following is a specification.

This invention relates to new and useful improvements in folding garment racks and it has more particular reference to a rack intended especially for the use of travelers, although applicable also for general domestic use, and which when extended will accommodate an ample number of garments and when folded shall be compact and may be packed away in a small space.

The present rack is especially adapted for trousers, its particular advantage in this connection being that each pair of trousers is separately displayed and removable from the rack without the necessity for manipulating any parts or for disturbing the arrangement of any other garment which may be hung on the rack.

5 A further advantage attained by the present invention is that the rack may be folded with the parts in their assembled relation; that is to say, it is not necessary to remove or separately pack any of the parts of the organized structure when the rack is folded.

The invention comprises more particularly a pair of pivoted supporting arms which carry removably assembled bars upon which the garments are hung and in connection with a construction of this general type it is the primary object of the invention to provide a novel construction, combination and arrangement of parts toward the ends of attaining the advantages stated.

40 In the accompanying drawings I have illustrated a preferred and advantageous embodiment of the invention, the structural details of which will be set forth at length in the description which follows, while the novel features by which the invention is distinguished from prior devices will be set forth in language of the proper determinative scope in the claims appended at the end of the description.

50 In the said drawings: Figure 1 is a perspective view of a folding garment rack constructed in accordance with the present invention, the rack being extended. Fig. 2 is a side elevation thereof. Fig. 3 is a front elevation showing the relation of the elements at one side of the rack when the structure is

folded, the elements at the other side of the rack being exactly similar. Fig. 4 is a side elevation of the rack when folded, the garment supporting bars being omitted. Fig. 5 is a detail perspective view of one of the bracket supports, the other being exactly similar. Fig. 6 is an elevation of one of the garment supporting bars, and Fig. 7 is a detail perspective view illustrating the end construction of the garment supporting bars and by virtue of which said bars are held from rotation.

Similar characters of reference refer to corresponding parts throughout the several views.

For convenience, the rack is preferably attached to a wall or other support by a pair of brackets, as 1, the construction of which is shown more particularly in Figs. 4 and 5. Each bracket 1 is of L-shape cross section and includes an attachment flange, as 2, which is screwed or otherwise attached to the wall, and a rack supporting flange, as 3, which projects forwardly from the wall.

55 The bracket proper comprises a pair of supporting arms, as 4, and a pair of brace arms, as 5, each brace arm connecting a supporting arm and its corresponding bracket. The arms 4 are pivoted to the flanges 2 near their upper ends, as at 6, and the arms 5 are pivoted to the arms 4 near their rear ends, as at 7. Notches 8 are formed in the free ends of the arms 5 to receive connecting bolts, as at 9, the latter passing through openings, as 10, in the lower ends of the flanges 3 and through the notches 8. Wing/nuts, as 11, are mounted upon the bolts 10 and are tightened to frictionally bind the parts which are assembled in the manner above set forth.

80 The arms 4 are provided with aligned notches, as 12, which extend forwardly and downwardly from the upper edges of said arms. The garment supporting bars are shown at 13 and, in order that they may not form creases in the garments, are preferably of round cross section with corrugated or otherwise roughened surfaces to cause sufficient friction to prevent the garments from slipping. The bars 13 are provided at their 85 ends with projecting plates, as 14, which prevent the garments from slipping lengthwise from said bars when the latter are tilted, as in the operation of removing the same from the arms 4. The bars 13 are also provided at 90 their ends with axially projecting flat-sided trunnions, as 15, which fit conformably in

the notches 12 and, in order to prevent axial play, may be provided with enlarged heads, as 16. Each arm 4 is also provided near its rear end with a notch 17, extending from the lower edge of said arm and, when the rack is folded, registering with a notch 18 formed in the adjacent arm 5 and extending from the lower edge thereof. When the rack is folded the bolts 9 are passed through the registering openings 10 and notches 17 and 18, and the nuts 11 are employed to frictionally bind the parts and assure of the rigidity thereof in their folded relation, as shown in Figs. 3 and 4, and wherein each arm 5 is folded parallel to the corresponding arm 4.

The bars 13 may advantageously be associated with the arms 4 when the rack is folded, this arrangement being compact and convenient, and accordingly, the arms 5 and the flanges 3 are formed with notches 19 and 20, respectively, which register with the corresponding uppermost notches 12 and fit over the trunnions of the uppermost bar when the parts are folded. It is also of advantage that the arms 4 (which are preferably thin strips of metal) may be held against play or springing movement and for this purpose, tie rods, as 21, may be employed, these rods being pivotally secured to the wall by eye-screws and having hooked ends for engagement in eyes, as 22, provided on the arms 4. A number of such eyes may be arranged at intervals to allow of the use of tie rods of different lengths, as necessitated by the dimensions of the closet or other space in which the rack may be placed. The feature of providing for the removable assemblage of the bars 13 is also of particular advantage, and in this connection it may be stated that any one of said bars, together with the garments thereon, may be removed without in any way disturbing the other bars and the other garments. The lowermost bar may be removed by simply lifting the same from the arms 4. The other bars may be removed by lifting the same from said arms and then by passing the same under the arms, the bars being tilted slightly in accomplishing this action. This manner of removing the bars is easier and quicker than lifting the same over the other bars in advance thereof.

When it is desired to pack the device for traveling, the bars 13 are removed from the arms 4 and the bracket 1 are then removed from the wall, after which the parts are folded and tightened by the nuts 11 in the manner explained. The parts at each side of the rack form independent folded structures, which themselves take up a very small amount of space and which may be compactly arranged by placing the end portions of each arm 4 in the angular space formed by the flanges 2 and 3 of the other structure.

The bars 13 may be packed together in a small space and separately from the rack or 65 with the folded rack structures, as desired, the space occupied by all the parts when knocked down being very small.

The present structure possesses all the particular advantages mentioned in the introductory paragraphs of the description, to which may be added the general advantages of simplicity of structural details, inexpensiveness, lightness, rigidity and strength.

Having fully described my invention, I 75 claim:

1. A folding garment rack comprising a pair of brackets, supporting arms pivoted to the brackets, a brace arm pivoted to each supporting arm, a bolt passing through each 80 bracket and the adjacent brace arm and binding the same together, each supporting arm and the brace arm pivoted thereto having openings which register when the brace arm is folded parallel to the supporting arm, 85 said bolt being then passed through the registering openings in said supporting arm and said brace arm, a nut threaded upon said bolt to bind the parts and garment supporting bars associated with said supporting arms. 90

2. A folding garment rack including a pair of brackets, a supporting arm pivoted to each bracket, garment supporting bars associated with the supporting arms, a brace arm pivoted to each supporting arm, the brace arms 95 being foldable to positions at the sides of the supporting arms and the latter being foldable to positions at the sides of the brackets, and means detachably connecting the brackets and the brace arms to hold the supporting 100 arms extended and connecting the brackets, the supporting arms and the brace arms when the parts are folded, each bracket, the supporting arm pivoted thereto and the brace arm pivoted to said supporting arm 105 being disposed and connected in folded relation as a self-contained unit.

3. A folding garment rack comprising a pair of brackets of L shape in cross section, each having an attachment flange and an 110 outwardly projecting flange, a flat supporting arm pivoted to each outwardly projecting flange and foldable to a position at one side thereof, a flat brace arm pivoted to each supporting arm and foldable to a position at one 115 side thereof, means connecting the free ends of the brace arms and each corresponding bracket and garment supporting bars removably associated with the supporting arms.

In testimony whereof I have hereunto set 120 my hand in presence of two subscribing witnesses.

AUGUSTUS MAY.

Witnesses:

GUS. HERO,
ANDREW HERO.

It is hereby certified that in Letters Patent No. 927,369, granted July 6, 1909, upon the application of Augustus May, of New Orleans, Louisiana, for an improvement in "Folding Garment-Racks," errors appear in the printed specification requiring correction as follows: In line 85, page 1, the reference-numeral "2" should read *3*; line 93, same page, the reference-numeral "10" should read *9*; line 54, page 2, the word "bracket" should read *brackets*, and the name of the first witness to the signature to the specification "Gus Hero," should read *W. S. Hero*; and that the said Letters Patent should be read with these corrections therein that the same may conform to the record of the case in the Patent Office.

Signed and sealed this 3rd day of August, A. D., 1909.

[SEAL.]

F. A. TENNANT,
Acting Commissioner of Patents.
